UNITED STATES PATENT OFFICE

1,978,409

MECHANISM AND MECHANICAL METHOD
FOR MAKING RUNPROOF OR RUN-RE-
SISTANT FULL-FASHIONED HOSIERYEllsworth E. Carlson, Saratoga Springs, N. Y., as-
signor to Van Raalte Company, New York,
N. Y., a corporation of New York

Application May 1, 1934, Serial No. 723,298

32 Claims. (Cl. 66—135)

This invention relates to mechanism and mechanical method for making run-proof or run-resistant full-fashioned hosiery and particularly to such mechanism and method for making the 5 full-fashioned hosiery or blank therefor disclosed in my co-pending application Ser. No. 700,193, filed November 29, 1933, as a continuation as to all common subject matter of my earlier co-pending applications Ser. No. 541,245, filed June 1, 10 1931; Ser. No. 613,244, filed May 24, 1932, and Ser. No. 645,919, filed December 6, 1932.

In order that the principle of the invention may be readily understood, I have disclosed in the accompanying drawings a single embodiment of 15 the mechanism of my invention, and whereby the mechanical method thereof may be carried out.

In said drawings:

Fig. 1 is a front elevation showing two sections and a part of a third section of a full-fashioned 20 knitting machine constructed in accordance with my invention;

Fig. 2 is a left hand end elevation of the mechanism shown in Fig. 1;

Fig. 3 is a vertical transverse section on the line 25 3—3 of Fig. 1, showing the needle bar cam and the presser cam and parts operated thereby;

Fig. 4 is a vertical transverse section on the line 4—4 of Fig. 1, showing the catch bar cams and parts operated thereby;

Fig. 5 is a vertical section on the line 5—5 of Fig. 1, showing the lapping cam and the parts moved thereby to swing the warp thread fingers between the needles;

Fig. 6 is a front elevation of the mechanism 35 shown in Fig. 5;

Fig. 7 is a plan view of the upper part of the mechanism shown in Figs. 5 and 6;

Fig. 8 is a detail in longitudinal section on the line 8—8 of Fig. 5;

Fig. 9 is a plan view of the so-called pattern cam and connections therefrom for imparting the endwise movements to the rod carrying the warp thread fingers;

Fig. 10 is a side elevation of the mechanism 45 shown in Fig. 9;

Fig. 11 is a vertical transverse section on the line 11—11 of Fig. 10;

Fig. 12 is a front elevation to show the warp thread fingers, supporting means, etc. for one 50 section of the machine;

Fig. 13 is a plan view of the parts shown in Fig. 12;

Fig. 14 is a vertical transverse section taken 55 through the warp thread finger rod, the narrowing point bars and the needle supporting mecha-

nism to show the relative position of the parts supported thereby;

Fig. 15 is a diagram to indicate the movements imparted to the warp thread fingers through the conjoint action of the lapping and pattern cam; 60

Fig. 16 is a plan view of the warp beam for one of the sections and certain of the immediate associated parts;

Fig. 17 is a plan view of one of the guide plates shown in Fig. 16, through openings in which 65 the warp ends pass;

Fig. 18 is an end elevation of the warp beam tension rod and immediately associated parts;

Fig. 19 is a vertical transverse section through a warp beam and the associated tension rod; 70

Fig. 20 is a horizontal longitudinal section taken through one of the warp beams on the line 20—20, Fig. 18;

Fig. 21 is a vertical cross section taken through a tension rod and the associated guide plate; 75

Fig. 22 is a plan view of the right hand end of the mechanism and particularly showing the screws and immediately associated parts for operating the narrowing points and the weft or body thread carriers;

Fig. 22a is a detail showing a guide and immediately associated parts for positioning properly with respect to the sinkers, etc. each weft or body yarn or thread as it is brought into action; 80

Fig. 23 is a front elevation of the mechanism shown at the right hand end of Fig. 22;

Fig. 24 is an end elevation of the mechanism shown in Fig. 22;

Figs. 25, 26, 27, 28, are somewhat diagrammatic views to indicate successive positions of a needle, a transfer point and a sinker in the transferring of a stitch composed of a portion of the weft thread and of the warp thread to the next adjacent wale;

Fig. 27a is a diagram for purposes of contrast with Fig. 27 to show the prior art;

Fig. 29 is a detail of a portion of the resulting fabric of my invention to show transferred stitches, in narrowing;

Figs. 30, 31 and 32 are side elevations respectively of the transfer point or narrowing cam, the needle cam and the sinker cam with indications thereon respectively of the control of the movements of a transfer point, a sinker and a needle for the positions of Figs. 25, 26, 27 and 28; 100

Figs. 33, 34, 35 and 36 are details in vertical section taken through the needle bar, catch bar and sinker support, to show the position of parts corresponding to each of the positions of parts in Figs. 25, 26, 27, 28; 110

Fig. 37 is a plan view of the blank made by the mechanism herein disclosed;

Fig. 38 represents the lower portion of the blank shown in Fig. 37, but trimmed and having the 80 sides and sole of the foot and the toe knitted thereonto;

Fig. 39 is a side elevation of the lower part of a full-fashioned stocking knitted in accordance with my invention;

16 Fig. 40 is a diagrammatic detail to indicate how the reinforcing weft threads are laid to make the reinforcements shown in the lower part of Fig. 37; and

15 Fig. 41 is a greatly enlarged plan view of a portion of the fabric of the stocking at certain of the narrowings, said view corresponding to a photograph of the fabric as made by a microscopic camera.

20 In my co-pending application Ser. No. 700,193, filed November 29, 1933, I have disclosed a run-proof or run-resistant full-fashioned stocking and blank therefor. The mechanism of this application is for the purpose of knitting the fabric disclosed and claimed in that application and which 25 is shown in Fig. 37 hereof. The said fabric is a plain knitted fabric made upon a full-fashioned hosiery machine preferably having a large number of sections, upon each of which a stocking leg or, if desired, a stocking leg and instep of the foot 30 is knitted. The said fabric is rendered run-proof or strongly run-resistant by reason of the fact that a separate warp thread is introduced into each needle wale of the fabric as hereinafter fully disclosed.

35 Any suitable hosiery yarn or thread may be employed as the main or weft yarn or thread, as, for example, silk, artificial silk, rayon, cotton or wool. In said Fig. 37, I have represented at 1 a blank which includes the leg, the ankle and 40 the heel. The stocking has a turned welt at its upper end indicated at 2 which may be of the usual type, but wherein the said warp threads are incorporated. The main or weft yarn or thread may be changed from time to time in knitting the stocking as may be necessary, as, for 45 example, at the end of the welt 2. Also reinforcing yarns may be introduced at the desired points as, for example, in the heel and high splice thereof, as indicated at 3 and along the opposite 50 edges of the instep portion as indicated at 4-4 in Figs. 37 and 38.

55 The fabric is knitted from the main or so-called weft yarn or thread indicated at 5 in numerous figures of the drawings, such, for example, as Figs. 25 to 29, and 41, and a series of warp threads one for each needle wale of the entire fabric, such warp threads being indicated at 6 in said figures. It is the main purpose of my invention to provide mechanism to make a fabric which is run-proof in both directions or run-resistant throughout the entire extent thereof. This I accomplish in accordance with the disclosed embodiment of the mechanism of my invention by introducing, as stated, into each needle 60 wale a separate warp yarn or thread 6.

65 Each of the warp yarns or threads 6, which themselves may be of any suitable material, but are preferably silk and of the same color and character as the main or weft thread, is introduced by means of a guide bar or rod indicated at 7 in cross section in Fig. 14 and in side elevation in Fig. 12, said guide bar having the warp thread guide fingers 8, one for each needle 9, the latter being spring beard needles. The said warp guides 75 8 are mounted in suitable relation to the needle

bar or support 10. The guides and the needles are shown merely diagrammatically and not for the purpose of showing the actual number or the actual spacing thereof. It will be understood that the number of needles 9 and the number of warp guides 8 are sufficient for the purpose of knitting the stocking and that as many heads or units will be provided in the machine as may be necessary. The said main or weft thread 5 is introduced in the manner usual in full fashioned machines, being traversed from edge to edge of each section of the fabric, and the loops or stitches of the said main or weft yarn or thread are formed in the manner usual in full fashioned machines.

90 As clearly shown in numerous figures of the drawings, each warp yarn or thread 6 is introduced into all the loops of its own needle wale only. The main or weft yarn or thread 5 is introduced in the usual manner by a thread guide or carrier 11 that is traversed back and forth the entire width of the fabric. As hereinafter more fully described, the fashioning of the fabric is effected by the lateral transfer of loops or stitches composed respectively of portions of the corresponding warp threads 6 and portions of the main or weft thread 5, the steps in the said lateral transfer being diagrammatically indicated in Figs. 25 to 28, wherein the successive positions of a needle 9, a transfer point 12 and the cooperating sinker 13 are shown.

95 As shown in Figs. 25 to 29, and 41, each warp 100 yarn or thread 6 lies in parallelism with the loop of the main or weft knitting yarn or thread 5 as shown, and at the top of the loop the yarn or thread 6 passes to a face of the previous loop and the portion of the yarn or thread 6 thereof and then passes down through the next loop when the same has been completed, passing to the last 110 mentioned face of such loop, and then participates in the formation of the next loop in the next course, the described operation being 115 continued from course to course. The said warp threads or yarns 6 do not enter into or become incorporated in sinker wales.

120 Each and every needle stitch is accurately measured by reason of the fact that in full fashioned machines, the sinkers 13 and the dividers apportion accurately the amount of thread which shall enter into each needle loop and the spring 125 beard needles 9 are all drawn down together. This avoids the inevitable slight robbing incident to the production of circular knit fabrics made by independently operated needles.

130 Inasmuch as each and every needle stitch or loop is thus accurately measured and its size determined upon, I apportion coordinately each needle loop or stitch of each warp thread 6 as to the length of thread constituting the same, to the accurately measured corresponding 135 needle loop or stitch of the body or weft thread 5. The result is that the normal lateral expansibility of the entire stocking incident to the drawing of the sinker loop upon the cooperating needle loop in the use of the stocking is fully preserved 140 notwithstanding the non-run character of the stocking, by reason of the said apportionment of the proper amount of one of the warp threads 6 to each measured corresponding needle loop or stitch of the main body or weft thread 5.

145 In order to incorporate the said warp yarns or threads 6 with the main or weft yarn or thread 5, I impart to the support for the warp guide bar or rod 7 a longitudinal movement (that is, one lengthwise of the machine) and also a 150

rocking movement (that is, one transverse to the knitting needles 9). The construction and co-operation of parts are preferably such that each warp yarn or thread guide 8 enters between two needles 9 from rear to front, is then moved lengthwise the machine a distance of one needle, is then swung rearwardly so that each such thread guide 8 passes between two needles and is then moved longitudinally in the opposite direction thus completing a generally rectangular path but with one rounded corner, all as diagrammatically indicated at 14 in Fig. 15, the said rounded corner indicated at 15 being due to the shape of the controlling cam.

In order to impart the necessary movements to the following members respectively, namely, to the rod for the narrowing points 12, to the needles, to the catch bar 21x that controls or operates the sinkers and dividers, and to the rod 7 that supports the warp thread fingers 8, I mount upon the cam shaft 16 of the machine, shown most clearly in Fig. 1, and which may extend the entire length of the machine, a series of cams indicated generally in Fig. 1 and the substantially exact contours of certain of which are shown in other figures of the drawings to be hereinafter referred to. In Fig. 1 (reading from the right hand end of said figure), the first cam, being that indicated at 17, is the so-called pattern cam that imparts the endwise movement to the rod 7 for the warp thread fingers 8. Next in order is the cam 18 known as the narrowing cam to control the movements of the narrowing points 12. Next to the left is the cam 19 termed the presser cam, for effecting the pressing of the beards of the needles 9. Next to the left is the cam 20 known as the needle cam for imparting the up and down movements to the needles by moving the needle bar 10. Next to the left is the front catch bar cam 21 for moving up and down the catch bar shown at 21x in Figs. 33 to 36, and elsewhere. Next to the left is the so-called back catch bar cam 22 for controlling or effecting the in and out movement of the sinkers and dividers represented in Figs. 33 to 36, and elsewhere. And finally at the extreme left of Fig. 1 is represented the so-called lapping cam 23 which effects or controls the to and fro or swinging movements of the warp thread fingers 8 between the needles. All of said cams are desirably made in two parts fastened together as indicated in Fig. 1, so that when the cam shaft 16 is moved axially, the follower for each of the said cams will rest either upon the part thereof which controls during straight or ordinary knitting or rests upon the part thereof which controls during narrowing.

The machine is provided with suitable framing uprights, two of which are indicated at 24 and 25 in Fig. 1, and positioned thereabove about midheight of the machine as shown in Fig. 1 is a bed piece 26. Rising from the said bed piece 26 are a number of brackets one at the end of each section and which are generally indicated at 27 in the several views of the drawings and particularly in Figs. 1 and 2. As shown in Fig. 2, each bracket 27 has a foot 28 suitably secured to the bed piece 26. Each bracket 27 has a suitable open bearing 29 to receive the shaft 30 of a warp beam, the cylindrical portion of any one of which is indicated at 31 in Fig. 20 and elsewhere. There is a warp beam for each section of the machine and in the particular machine herein shown each shaft 30 supports one such warp beam.

While the warp beam may be of any suitable construction, I have represented the following construction in Fig. 20.

For each warp beam there are provided two collars 32, 33 made fast by screws 34 to the shaft 30. The tubular portion 31 of the beam is received at its heads directly upon the collars 32, 33, and is made fast with respect thereto by reason of a key 35 shown near the right hand end of Fig. 20. Tightly secured or fast upon the ends of the tubular portion 31 of the beam are the heads 36, 37, between which all the warp thread ends are carefully wound. Outside one end of the tubular portion 31 is a so-called friction band pulley 38 secured by one or more screws 38a to an end of the tubular portion 31. About the pulley 38 is passed a cord or rope 39 shown most clearly in Fig. 16. Said band 39 is passed one or more times about the said friction band pulley and one end thereof is secured at 40 (see Fig. 16) to a stud upon a bracket 41 itself secured to and extending laterally from the upper part of the bracket 27, as shown most clearly in Fig. 2. The other end of said band or cord 39 has secured thereto a suitably shaped wire or member 42 upon an upturned portion whereof are received a number of weights 43 which may be varied in number or size as desired.

The bracket 41 (shown also in Fig. 18) is of a general right angled form and in the outer end 44 thereof is received in a threaded part a screw 45 whereon is a wing nut 46 to vary the tension of a coiled spring 47 whose opposite end is fast at 48 to the support for a tension rod 49 mounted at each end or at suitable intervals in the lower end of a bracket or arm 50 depending from the right angled bracket 41. Suitably secured to the said tension rod 49 is a so-called brass plate 51 shown most clearly in Figs. 16, 17 and 21.

For convenience of manufacture and design I herein provide three so-called brass plates 51 for or pertaining to each warp beam and I have shown the same in Fig. 16. As therein appears, the brass plate 51 to the extreme left is of a smaller area than the other two. Each of the said brass plates 51 is provided with a multiplicity of holes in each of which is set a porcelain eye 52 through which a warp thread passes and which is by said eye 52 prevented from being cut by the metal of the plate 51. Each plate 51 is directly secured to the tension rod 49 by a bent plate or member 53 secured by a suitable number of screws 54 to the tension rod 49.

The brass plates 51 are set at the proper angle to receive and guide most effectively the warp threads which are generally indicated at 6, in the several figures such as 2, 18 and 19. The pull of the said warp thread 6, which is suitably controlled by the friction band 39, etc., is toward the right viewing Fig. 18, and such pull is resisted by the coiled spring 47, as described.

I shall next refer to the means for imparting lengthwise or axial movements to the rod 7 for the warp thread fingers 8, and for this purpose shall refer particularly to Figs. 1, 12 and 13.

The pattern cam 17 receives thereagainst a roll 55 which is suitably supported in an adjustable upright rod or connecting member 56 pivoted at its upper end at 57 to the arm 58 of a lever pivoted at 59 on a bracket 60 secured to a bed piece 61. The so-called upright rod or connecting member 56, comprising, as it does, a sleeve threaded at each end onto a threaded connection, is more particularly hereinafter described. The upright arm 62 of said lever 145

presses against the adjustable end 63 of the said rod 7, and through the action of the so-called pattern cam 17 the said rod 7 is moved toward the left viewing Fig. 1. At every other section 5 of the machine (and as shown in Fig. 1 and upon a larger scale in Fig. 12), there is provided a coiled spring 64 surrounding the said rod 7 between one of the brackets 27 and a collar 65 fast upon the said rod. The purpose of the said 10 springs is to move the said rod 7 toward the right viewing Figs. 1 and 12.

The warp thread fingers 8 are secured in suitable numbers, one for each needle, in blocks or plates 66, the parts of which are secured together by screw 67. Desirably, the said fingers 8 are not as to any of them swung in small or large groups into and out of operative position, but instead I provide means whereby the entire set of warp thread fingers 8 for a single section of 15 the machine may be manually swung into inoperative position for any purpose, as, for example, for getting at the narrowing points 12. While for this purpose any suitable construction 20 may be provided, I preferably provide the following arrangement.

The several blocks or plates 66 are suitably secured to or carried by plates 68 depending from bearings 69, 70, both loosely mounted upon the rod 7. Upon the said rod there are fast in addition to the collar 65 two collars 71, 72, the latter having two suitably spaced recesses 73, 74, in either of which may be received a projection or tongue 75 adjustably secured as shown in the bearing block 70. Between the fast collar 71 and the loose bearing block 70 is a coiled spring 75a tending to move the loose bearing block 70 toward the fast collar 72 so as to hold the tongue 75 in whichever recess 73 or 74 thereof it may be engaged with. It is evident that by manually withdrawing the tongue 75 from the fast collar 72 by 30 sliding the block 70 against the tension of the spring 75a, the entire set of warp thread fingers may be swung about the rod 7 as an axis into either an operative or an inoperative position.

The warp thread fingers 8 may be of any suitable construction such as disclosed in other co-pending applications of mine and need not be herein more particularly described.

I have referred generally to the pattern cam as 17, the narrowing cam as 18, the presser cam as 19, the needle cam as 20, the front catch bar cam as 21, the back catch bar cam as 22, and the lapping cam as 23. In reality each of said cams is composed of two disks or parts secured together 50 in face to face relation and in each case the part known as the narrowing side is characterized by the exponent *a* and the knitting side by the exponent *b*. As is well known, the cam shaft of the Reading full-fashioned machine and of certain other full-fashioned knitting machines is moved axially just prior to each narrowing operation. It is unnecessary to describe in detail the shape of 55 all of said cams both as to the narrowing side and the knitting side as certain of said cams are of usual shape and function in the usual manner.

Having described in detail the pattern cam 17 made up of the two disk portions 17a, 17b, I will next describe the lapping cam 23 composed of the two disks 23a and 23b and the operative connections between the same and the shaft 7 on which the warp thread fingers 8 are mounted, and in doing so will refer to Figs. 5 to 8 inclusive.

As shown best in Figs. 5 and 6, the front girt 76 has rising therefrom a bracket 77 upon which is pivoted at 78 an upright lever 79, the upper end

80 of which is connected by a link or rod 81 to a slotted arm 82 fast upon the warp finger rod 7. Said lever 79 has a roll 83 held by spring 84 against the periphery of the disk 23a or the disk 23b of the lapping cam 23. Preferably I provide an adjustable or variable connection between the lever 79 and the rod 81 for the purpose of permitting the warp fingers 8 to be moved manually as a set into inoperative position. This I preferably do in the following manner.

As shown most clearly in Figs. 5 and 8, the link or rod 81 has an ear 85 whereon is pivoted a hand lever 86 held in the position shown in Fig. 8 by coil spring 87. At its inner end the said lever 86 engages a slideable pin 88, the free end of which is adapted to enter a hole 89 near the upper end of said lever 79 or to be withdrawn therefrom and brought by upward swinging movement of the link or rod 81 into position to be similarly engaged in a like opening in the extreme upper end 90 of said lever arm 79 as indicated in dotted lines in Fig. 5. When the pin 88 is engaged in the opening at 90 in the extreme upper end of the lever 79, the warp fingers are swung into inoperative position, thus permitting access to the needles or for the purpose 95 of permitting ready threading of the warp fingers 8. It will be observed that the outer end of the rod or link 81 may be grasped by the hand together with the adjacent end of the lever 86, for the purpose of sliding the pin 88 as described.

It will be observed that the said pin 88 is directly received in a support 91 that surrounds the upper end of the lever 79 and the link or rod 81 at all times, and permits the latter to be moved to or from the full line position shown in Fig. 5.

I will next refer to certain adjustable connections between the lapping cam 17 and the warp thread rod 7 for effecting adjustment of the extent of the lengthwise movement of the warp thread finger rod 7.

I have referred to the upright rod or connecting member 56 as adjustable. The construction preferably employed by me for effecting such adjustment is best shown in Figs. 2, 9, 10 and 11. Therein the back girt is indicated at 92 and thereon is fast a bracket 92a whereon is pivoted at 93 an arm 94 at the outer end whereof is mounted the roll 55 to bear upon either portion 17a or 17b of the pattern cam 17. The lever arm 94 has a lengthwise slot 96 receiving the two members 97, 98, secured together by bolts 99 and connected to the lower end of the lowermost threaded connection 100 which itself is threaded at its upper end, as clearly shown in Figs. 1 and 2, to provide an adjustable connection with the sleeve of the so-called adjustable connection 56. At the opposite ends of said sleeve are nuts (shown in Figs. 1 and 2), the lowermost of which engages said lowermost threaded connection 100. The upper nut engages a similar threaded connection 100 which, as previously described, is pivoted at its upper end at 57 to the lever arm 58. By loosening the nuts, the said sleeve may be turned in either direction to make a fine adjustment. Mounted in lugs 101, 102 on the lever arm 94 is a turn screw 103 which is confined against longitudinal movement but by the turning thereof the two members 97, 98 are slid along the slot 96 and hence toward or from the pivot 93 of the lever arm 94. This obviously varies the length of throw of the adjustable arm 125 or member 56 during the rotation of the pattern cam 17, and thereby I may vary or accurately adjust the lengthwise movement of the warp finger supporting shaft 7.

I will next refer to the needle cam 19 composed 130

of the two disk members 19a and 19b, and for that purpose make reference to Fig. 3.

Against the periphery of the needle cam 19 rests a roll 104 which is pivotally mounted near the lower end of a depending lever arm 105 itself pivoted upon the shaft 106 extending lengthwise the machine frame. The said depending lever 105 has two notches, one indicated in dotted lines at 107 and the other one of which, 108, is shown as receiving a transverse pin 109 on a hand lever 110 extending transversely of the machine somewhat above the cam shaft 16. At its inner end said hand lever 110 is pivoted at 111 to the depending lever arm 112 for the needle bar, itself pivoted at 113 upon the member 113a, so as to swing the needle bar 10 to and fro to effect pressing the beards of the needles in the usual manner.

At its lower end the lever arm 105 has connected thereto one end of a coiled spring 114 which at its other end 115 is connected to the framing of the machine, so as to hold the roll 104 against the periphery of the presser cam 19.

I will next describe the so-called needle cam 20 composed of the two disk members 20a, 20b, and for that purpose will make reference to Fig. 3 and also to the diagrammatic illustration of the narrowing side 20a of the said needle cam 20 in Fig. 31.

The said needle cam 20 is fast on the cam shaft 16 and against the periphery thereof rides at all times a roll 116 pivoted near the lower end of a depending lever arm 117, which itself is pivoted upon the needle bar shaft 118, as shown in Fig. 3. At its lower end the said lever arm 117 has connected thereto one end of the coiled spring 119 which at its opposite end, as shown at 120, is connected to a suitable bracket 120a upon the machine framing. In order to cooperate with the spring 119 in insuring contact at all times between the roll 116 and the periphery of the needle cam 120 at the knitting side 20b thereof and to prevent making the spring 119 too heavy, I provide a so-called box cam 121 shown in Fig. 3 as of segmental shape and as fast upon the cam shaft 16. The outer end of said box cam 121 is flanged so as to overlie and engage, by its under face in its rotation with the cam shaft, the periphery of the roll 116 and prevent any tendency of the said roll to separate from the periphery of the cam 20 at the time of greatest strain, i. e. when the needles rise through the said double loops. The warp loops place an extra strain on said spring and might prevent it from keeping the roller on the cam when said roller leaves the high point of the cam after the knock-over.

In Fig. 31, I have represented substantially the exact contour of the narrowing side 20a of the said needle cam 20, and have applied legends at various parts of the periphery of the said cam 20 to indicate the correlation of the movements of the needles 9 with the movements of the narrowing points 12 and the sinkers 13 in the narrowing operation, as indicated in the diagrammatic views 25 to 28. The legends of Fig. 31 set forth the positions of the needles 9 throughout their movements in narrowing and the corresponding positions of the narrowing points 12 and the sinker 13 (and dividers) and should be read in connection with the legends upon Figs. 25 to 29 (as well as the legends upon Figs. 30 and 32).

I will next describe the front catch bar cam 21 and for that purpose will refer to Fig. 4 and also to the sectional views 33, 34, 35, 36.

Said cam 21 is composed of the two disks, name-

ly, 21a constituting the narrowing side, and 21b constituting the knitting side. Against the periphery of the said cam 21 rests the roll 122 pivotally mounted at the lower end of a lever arm 123 itself pivoted upon the front catch bar lever shaft 124 from which laterally extends a lever arm 125 connected at 126 to or having an upright member 127. The latter is suitably connected at 128 to the part 129 of the catch bar 21x. Said part 129 is pivoted at 130 at the upper end of a lever arm 131 itself pivotally mounted at its lower end upon the back catch bar lever shaft 132, which is mounted in a suitable bracket 133 on the machine frame.

The purpose of the front catch bar cam 21 is to impart up and down movements at the proper time to the catch bar 21x so as to cause the same to engage the butts of the sinkers 13 and of the dividers, so that at the proper time said sinkers and dividers may be moved toward and from the needles through the agency of the back catch bar cam 22.

The positions of the parts shown in the sectional views 33 to 36 correspond substantially to the positions of the parts in the diagrams 25 to 28, and will be further referred to when describing the narrowing action.

I will next describe the back catch bar cam 22 and for that purpose will make reference to Figs. 4, 27, 32 and 35.

Said cam 22 is composed of the two disks 22a, 22b and against the periphery of said cam bears the roll 134 at the lower end of the lever arm 135 fast as shown in Fig. 4 upon the back catch bar lever shaft 132. A spring 136 connected at one end to the lever arm 135 and at its other end to a bracket arm 137 upon the machine frame, is provided to hold the roll 134 at all times against the periphery of the cam 22.

The knitting side 22b of said cam is shaped as usual, but the narrowing side 22a thereof has been changed from the usual formation of the narrowing side of the back catch bar cam so as to provide a depression or relatively small concavity 138, best shown in Fig. 32, opposite the legend reading "Narrowing points delivering stitches to needles". The purpose of the said formation 138 is slightly to retard or delay the inward movement toward the needles of the sinkers 13 (and dividers) so as to cause the said sinkers (and dividers) to assume the position indicated in Fig. 27 and in Fig. 35. It will be noted from Fig. 26 and Fig. 34 that the sinkers 13 have in their inward movement neared or substantially reached a vertical plane touching the outermost portions of the needle beards therebelow. If the usual formation of the narrowing side of the back catch bar cam 22a were employed, the sinkers (and dividers) would, when the narrowing points 12 have reached the position shown in Fig. 27, have themselves moved inward (that is, to the left viewing Figs. 25 to 28) substantially farther than as shown in Fig. 26. I have discovered that if such movement occurs at such time, there is a grave tendency of the sinkers (and dividers) to get under the fabric, especially as said warp threads are being shifted with the weft thread each to an adjacent needle wale, as indicated in Figs. 26 and 27. This causes a so-called "fly out" and permits the fabric to rise with the needles, thus preventing the proper casting off so that the needles become "loaded". Therefore, I retard or delay the said inward movement of the sinkers 13 (and dividers) so that their position, when the transfer points 12 are positioned as shown in Fig. 27, is

80

145

still such that they do not contact with the stitches that are being transferred. When, however, the depression or formation 138 of narrowing side 22a of said catch bar cam 22 passes from under the roll 134, the sinkers 13 (and dividers) quickly move into the position indicated in Fig. 28 and also in Fig. 36, thus completing the movement of the sinkers and dividers toward or between the needles, in a direction toward the left viewing Figs. 25 to 28.

I will next describe the narrowing points cam 18 having the two disk portions 18a and 18b, the latter of which is a true circle, because, of course, during the usual knitting as contrasted with narrowing, the narrowing points remain entirely stationary.

Referring to Fig. 2 and also to Fig. 30, the narrowing points cam 18 has resting upon the periphery thereof a roll 139 pivotally mounted upon a horizontally extending lever arm 140 itself pivoted at 141 upon the framing. To the said lever arm 140 is pivotally connected at 142 an upright link or connecting rod or bar 143, the upper end whereof is shaped as best shown in Fig. 2, and is there suitably connected to the rod 144, shown also in Fig. 14 as extending longitudinally of the machine for supporting the narrowing bars 145, 146 that themselves support the two sets of narrowing or transfer points 12 for each section 30 of the machine. The said narrowing rod 144 is suitably supported by a plurality of operating arms, one of which is shown at 147 in Fig. 2 as mounted upon a pivot 148, so as to receive motion in the usual manner. The narrowing side 18a 35 of the narrowing points cam 18 is shaped as indicated in Fig. 30, and the legends thereon should be read in connection with the legends upon Figs. 25 to 28 as well as the legends upon Figs. 30 and 31, to understand the exact coordination of their 40 movements of the needles 9, the narrowing or transfer points 12 and the sinkers 13 (and dividers) in effecting the lateral transfer of stitches each composed of a portion of a warp thread 6 and a portion of the weft or main knitting thread 5, as clearly indicated in Figs. 25 to 28 and also Fig. 29. As best shown in Figs. 26 and 27, while the narrowing or transfer points 12 are moving stitches laterally as described, the sinkers 13 (and dividers) are kept substantially or entirely 50 from engagement with the said stitches and thus from getting under the fabric, with the grave results hereinbefore stated.

My invention is not limited to retarding or delaying the movement of the sinkers 13 (and dividers) toward the needles at the time of such lateral transfer, since so far as I am aware I am the first to provide means for laterally transferring or shifting stitches composed of warp threads and the main weft thread.

At the time of such lateral transfer of stitches, whether to the extent of one needle wale or more, I maintain or preserve preferably the same tension upon all the warp threads that I preserve during the regular knitting operation, and which I have already described with respect to Figs. 16 to 21. The warp threads should, of course, be preserved under sufficient tension at the time of lateral transfer of stitches to prevent any slackness in the stitches.

There is necessarily something of a tendency at the time the transfer points rise in their transferring movements, slightly to elevate the plane of the fabric at such place. As stated, I prefer to keep a uniform tension at all times upon the entire set of warp threads 6, but such tension is

rendered variable by the means already described.

In Figs. 27a I have indicated by way of contrast the position that would be occupied by the sinker 13 in Fig. 27 were it not for the cut-out or depressed portion 138 at the narrowing side 22a of the back catch bar cam 22. In Fig. 29, I have shown a few stitches in adjacent wales and courses where the lateral transfer is effected, and therein the same reference numerals are employed as in other figures of the drawings.

I will next briefly describe the screw mechanisms for moving the narrowing point bars 145, 146, and for the several weft thread carriers, and in so doing will refer to Figs. 22, 23 and 24. The two oppositely threaded portions that control the movements of the narrowing or transfer points 12 in a direction lengthwise the machine are represented at 149, 150 in Figs. 22 and 23. With them cooperate the other parts herein not necessary to describe in detail, since the movements of said parts may be and preferably are as usual.

The cam shaft 16, as shown in Fig. 24 (which is the right hand end of the machine viewing Fig. 1), is provided with a cam 151, which functions only when the cam shaft 16 has been axially moved to the right viewing Fig. 1 (that is, when the said cam shaft is moved axially for narrowing). When the shaft 16 is so moved, the cam 151 thereon is brought into vertical alignment 105 with a roll 152 upon a lever arm 153 pivoted at 154 upon the framing that is indicated in dotted lines in said Fig. 24. Therefore, at each revolution of the cam shaft 16 the lever 153 is lifted against the tension of the spring 155 connecting the end thereof to the frame, and reciprocates the yoke-like member 156. Upon said member 156 is pivoted at 157 a pawl 158 to engage the ratchet 159 and at 160 there is pivoted the pawl 161 to engage the ratchet 162, shown in Fig. 23. Suitable springs are provided to hold said pawls in proper functioning position.

In the disclosed embodiment of my invention I do not operate a ratchet in connection with the screw 163 (Fig. 22) for the weft thread carriers, 120 inasmuch as the blank is knitted of full width throughout, as hereinbefore described, and no adjustment of throw of the weft thread carriers is necessary, at least so far as the main carrier is concerned. I do, however, utilize three weft 125 thread carriers which are indicated diagrammatically at 164, 165 and 166 in Fig. 40. The carrier 164 is for the main or body weft thread and travels throughout the entire width of the fabric blank at each course throughout the knitting of 130 the blank. The carriers 165 and 166 are for the reinforcing threads that provide the reinforcements 3, 3 for the heel and the high splice as shown in Figs. 37, 38, 39 and 40, and for the narrower reinforcements 4 along opposite edges of 135 the instep portion of the foot, broadened out as shown in the vicinity of the toe, as represented in each of said figures. The traverse of the reinforcing thread carriers 165—166 may be varied in the general manner described in the patent to 140 Landenberger, No. 1,134,749, April 6, 1915. The purpose of the narrow reinforcements 4 is to provide a heavier area to be seamed to the upper side portions of the bottom of the foot indicated at 167, 168. Said edges are seamed together along 145 lines, one of which is indicated at 169 in Fig. 39, and in so doing the reinforced areas 4 are substantially covered by the said seaming threads. As I do not herein claim means for varying the length of traverse of the reinforcing thread car- 150

riars 165, 166, I have merely herein indicated them diagrammatically in Fig. 40.

I will next refer to means for guiding into proper position for introduction at either edge of each 5 blank the thread of each weft carrier when brought into action. For this purpose I shall refer to Figs. 12, 13, 22 and 22a.

Each of the weft or main or reinforcing knitting threads when not in action has its end held under a small turnbutton or like structure. In the 10 Reading machine equipped with the mechanism of my invention, similar turnbuttons are provided but are upon a raised portion of the casting 28, Fig. 2, with the consequence that when any weft 15 thread is thrown into action at either end of the bank of needles, the said thread is apt to come into action too high (i. e. over the sinkers). To overcome this objection, I have provided inclined guides at each end of each bank of needles, along 20 the under side of which each incoming weft thread in its first course is automatically moved so as to bring said thread to such a low level that it goes into action at the proper height or level with respect to the sinkers 13.

25 The turnbuttons, which may be otherwise of the usual construction, are shown at 170, 171 (best shown in Figs. 12 and 22). Upon the two stationary bars 172, 173 (best shown in Figs. 12 and 22 as extending in a direction from front 30 to back of the machine), there are provided two inclined wire or like guides 174, 175. Said guides are so positioned that the incoming thread takes the course or path represented in full lines at 176 in Fig. 22a instead of the path 177 indicated in 35 dotted lines in said figure, as would be the case if said guide were not provided. By reason of the employment of the said guide, each weft thread is brought into action substantially as indicated in Fig. 14.

40 Referring to Fig. 12, it will be observed that each warp thread finger 8 is set a little nearer the needle next to the left thereof (viewing Fig. 12) than the needle next to the right. The purpose of this arrangement is as follows. The laying 45 movement of the warp thread bar 7 is from right to left viewing Fig. 15 and referring to the path 15 is indicated in dotted lines in said figure. At the left side of the section such laying movement is balanced or offset by the inward movement of 50 the narrowing points 12, but at the right side of the section the movements of the said two elements or features (namely, the warp thread guides and the narrowing points) are in the same direction. Furthermore, after the loops have 55 been transferred, the warp threads must be gotten back to the right side of their original needles respectively. This means that each warp thread must cross two needles and wrap around the right side of the second needle. In doing so, it naturally 60 pulls such needle to the left. If the guides were centered and the needles tipped to the left, the guides might hit the needles in the act of passing between them. Therefore, I set the guides slightly to the left in order to let them pass those 65 needles which have been tipped to the left after the transfer of the loops.

I will now make reference to certain features which have not been particularly referred to in the foregoing description of the mechanism.

70 Referring first to Fig. 37, which shows the blank that is knitted by the mechanism herein disclosed and which blank as well as the resulting fabric and the method of making are claimed in my co-pending application Ser. No. 700,193, it is noted that in said Fig. 37 the three sets of narrow-

ings at three different portions of the fabric are indicated respectively at 178, 178a, 179, 179a, 180, 180a. The narrowings 178 and 178a are provided at the upper portion of the stocking below the welt, by transferring inwardly in the manner fully described, stitches composed of the main knitting or weft thread and the corresponding warp threads, thereby not only making the actual narrowings indicated diagrammatically in Fig. 37, etc. but also the inclined lines of holes parallel therewith, and along which holes the blank will be trimmed as fully described in my said co-pending application Ser. No. 700,193.

The narrowings 179, 179a are similar in character to those just described, but are provided for the calf or ankle portion and, of course, commence further inward with respect to the actual lateral edges of the blank. The narrowings 180, 180a are the heel narrowings and are made in the same way as those at 178, 178a, 179, 179a, but, it will be observed, include also the lateral transfer of the reinforcing weft threads at those areas. Thus, although the blank is knitted of the same width throughout, narrowings are provided wherever desired. The instep or top of the foot 100 portion is indicated at 181 and it will be understood that the warp threads 6 pertaining thereto are continued without interruption from the top of the stocking down the leg and instep to the toe 182, which is knitted as a continuation of the strips 167, 168 that are in the usual manner knitted on the footer after the heel tabs have been turned outwardly in the manner indicated at 183, 183a in Fig. 38.

In Fig. 37 and also partly in Fig. 38, I have 110 represented by dotted lines 184, 184, etc. warp threads which may be colored prior to their winding upon the warp beam, the purpose thereof being to guide the operative who trims the blank after the blank has been completely knitted. 115 The coloring matter used, of course, is such that it will disappear in further treatment of the blank. The fabric will, of course, be trimmed along the lines of holes outside the actual narrowings indicated in Fig. 37 in the manner described. It will, of course, be understood that I have not attempted in any of the figures of the drawings to show each narrowing, as, to do so would require that the figures be of the same 120 size as the hosiery itself.

As already described, the stitches at the points where the fashionings or narrowings are to be provided are transferred inward by the action of the narrowing points 12 in the manner fully described. Each stitch so transferred inward is 130 transferred to the extent of one or two needles, desirably not more than two, but the traverse of the main or weft thread carrier, such as 164 (Fig. 40), is continuous for the full width of the fabric, preferably down to the very end 185 of the blank 135 shown in Fig. 37, though, as pointed out in my co-pending application Ser. No. 700,193, the fabric need not be continued of the full width as far as the line 185.

Inasmuch as the warp threads 6 introduced by 140 the endmost warp guide fingers 8 of each section and those near thereto remain in action, it will be evident that the said warp threads 6 continue to be supplied to the same identical needles as before, although certain stitches are laterally shifted inward as indicated at 186 in Fig. 41 and also in Fig. 29. The result is to provide, as already stated, an inclined line of small openings (best illustrated at 187 in Fig. 41) along each side of the fabric. In Fig. 41, there is represented the 145 150

structure of the resulting fabric, and it will be observed that each of said openings 187 is traversed by one warp thread 6, such thread becoming at once incorporated in the further knitting 5 of the fabric as indicated directly below each of the openings 187 in Fig. 41. After the knitting of the entire blank has been completed, I trim off each edge of the blank along the lines of the holes 187 wherever they occur. This leaves entirely 10 acceptable edges because of the non-run character of the fabric and the lateral transfer of the stitches, and the two inclined edges are then seamed together in any suitable manner.

Referring again to the lapping cam 23 composed 15 of the two disks 23a and 23b, the point 188 thereof (most clearly shown in Fig. 5) is the formation that causes the swinging of the warp thread fingers 8 from the full line position shown in Fig. 14 to the dotted line position to the right thereof. 20 At the left hand side in Fig. 14 of the full line position, there is shown in dotted lines the position very briefly assumed by each of the warp thread fingers when the narrowing operation occurs. The said fingers 8 are thrown to the said 25 dotted position at the left by a suitable formation on the lapping cam 23a indicated in Fig. 5.

Referring again to the means for delivering or supplying the warp threads 6 from each warp beam 31, it is noted that along the top of the machine there extends a long rod or a plurality of rods 189 shown in Figs. 1, 2 and 18. The various brackets 41 receive and support the said rod or rods 189 and the brackets or arms 50 depend from the said rods 189 at or in the vicinity of 30 the said brackets 41. The construction and arrangement of the parts are such that the warps are guided entirely out of contact with all parts of the machine from the warp beam 31 down to the warp fingers 8 excepting that they pass 35 through the porcelain eyes 52 in the brass plates 51. This effectively prevents breaking or abrasion of the warp threads, due to contact with stationary parts of the machine. It also prevents the warp threads being displaced one with respect 40 to another, and insures the proper feeding or guiding of each warp thread 6 to its own warp finger 8.

Referring again to the pattern cam 17 (best shown in Figs. 2 and 10) the elevation or formation 50 of the periphery thereof is the formation which gives the endwise movement to the bar 7 from which are supported the warp thread fingers 8. By providing the very gradual elevation 190, I am enabled to move the warp thread bar 7 55 at the proper time and to drive the cam shaft 16 at a relatively high rate of speed. This results in increasing the speed at which the warp threads are lapped about the needles. I am also enabled to operate said bar 7 at a higher rate of speed by 60 reason of the fact that the raise or dip on the pattern cam has been very greatly reduced. This I have been able to accomplish by changing the cam working off the pattern cam and giving the axial movements to the guide bar shaft from a 65 vertical sliding cam, as illustrated. The illustrated relatively large flat or vertical inner face of the upright arm 32 is provided so that the same part may be used to operate the picot bar, of which no disclosure is made in this application.

70 I have stated that a separate warp thread is supplied to each needle wale throughout the width of the fabric. In actual practice, I may omit two or three warp threads at each edge of the fabric, inasmuch as the main or weft thread 75 sometimes misses the first or second needles of

the bank of needles, and if the warp threads were in the corresponding guides, they would be broken off if such defect in the laying of the main weft thread occurs. This, however, does not affect the appearance of the hosiery, as in actual practice several of the edge wales are always taken up in and by the seaming operation.

In Fig. 40, I have diagrammatically indicated 80 three weft carriers. It will be understood that in actual practice I usually employ four weft carriers, namely, one for the welt thread, one for the body thread, two reinforcing threads which includes the heel reinforcement, the seam reinforcement down the foot, and the toe reinforcement. The number of weft thread carriers may, however, be varied as desired, without affecting the invention herein disclosed.

In Fig. 40, I have diagrammatically indicated 85 three weft carriers. It will be understood that in actual practice I usually employ four weft carriers, namely, one for the welt thread, one for the body thread, two reinforcing threads which includes the heel reinforcement, the seam reinforcement down the foot, and the toe reinforcement. The number of weft thread carriers may, however, be varied as desired, without affecting the invention herein disclosed.

The lateral transferring or shifting at the narrowings of loops each composed of a portion of a main knitting thread and a portion of a correlated warp thread serves not only to provide the conventional fashioning or narrowing marks, but also to provide openings in the fabric, along which lines of openings the fabric is subsequently 90 trimmed. The more important purposes of the said lateral transfer of shift of loops are (1) to provide the conventional fashioning marks so that the fabric will not be merely cut hosiery, 95 (2) to shape the hosiery in the conventional manner, and (3) to provide wales running in the inclined direction of the fashioning, so that the subsequent seaming will be along the wales and not across them, which latter structure would 100 make a weak seam. The formation of the said 105 openings is important in providing lines along which the blank is subsequently cut.

Referring again to the diagrams Figs. 25 to 28, illustrating the lateral transfer of loops composed of the main weft thread and warp threads, 110 the sinkers 13 (and dividers) are retarded while the points 12 are delivering the loops to the respective adjacent needles, or, in other words, while said points are being lowered. When the points 12 rise with the fabric, they lift it above 115 the normal level or plane thereof, and when they deliver the loops to the respective adjacent needles, the said points lower the fabric again. The presence of the warp threads under tension tends to 120 keep the fabric higher than is the case in the regular full-fashioned operation, and it is mainly for this reason that I retard the inward movement of the sinkers 13 (and dividers) until the points 12 are low enough to make proper engagement with the fabric.

I have referred to the fact that when the narrowing occurs, the warp thread fingers 8 are moved into the dotted line position shown at the left in Fig. 14. During the regular knitting, however, the said warp thread fingers 8, in passing through threads about the needles in the path shown in Fig. 15, move into the dotted line position shown at the right in Fig. 14. Such movement in laying the warp threads is due to the fact that the rise 190 on pattern cam 17b and the higher point 188 on cam 23b are reached at 130 the same time. When the actual narrowing occurs (that is, when the stitches are being laterally transferred from one needle to another), the said guides 8 are thrown into the dotted line position shown at the left in Fig. 14 by the action of the narrowing side 23a of the lapping cam. The arc like path 15 in Fig. 15 is caused by the fact that while the guides 8 are being pushed through 135 and beyond the needles by the lapping cam 23, 140 the warp threads are being moved laterally by the action of the narrowing side 23a of the lapping cam. The arc like path 15 in Fig. 15 is caused by the fact that while the guides 8 are being pushed through and beyond the needles by the lapping cam 23, 145 the warp threads are being moved laterally by the action of the narrowing side 23a of the lapping cam. The arc like path 15 in Fig. 15 is caused by the fact that while the guides 8 are being pushed through and beyond the needles by the lapping cam 23, 150

they are also being pushed to the left by the pattern cam 17a, after they have passed between the needles, but before they have reached the end of such movement.

- 5 Having thus described one illustrative embodiment of the invention and the best mode known to me for practicing the method thereof, it is to be understood that although specific terms are employed, they are used in a generic and descriptive sense and not for purposes of limitation, the scope of the invention being set forth in the following claims.

I claim

1. In a full-fashioned hosiery knitting machine having knitting needles and cooperating sinkers, etc. to form successive courses of regular loops of the main knitting thread; main thread carrier means to traverse said main thread from edge to edge of the hosiery blank, warp thread guiding fingers to introduce separate warp threads into different needle wales of the fabric coincidentally with the laying of the respective courses of the loops of the main knitting thread; means acting at the hosiery narrowings so as laterally to transfer or shift loops, each of which is composed of a portion of the main knitting thread and a portion of a correlated warp thread to provide openings in the fabric, together with means for continuing the knitting of the fabric of the full width for a substantial plurality of courses beyond said openings and continuing in such courses the introduction of the separate warp threads into their same needle wales as before.

2. In a full-fashioned hosiery knitting machine having knitting needles and cooperating sinkers, etc. to form successive courses of regular loops of a main knitting thread; main thread carrier means to traverse said main thread from edge to edge of the hosiery blank; warp thread guiding fingers to introduce a series of warp threads into different needle wales of the fabric coincidentally with the laying of the respective courses of said loops, transfer points adapted to enter loops each composed of the main knitting thread and the correlated warp thread, means to shift said points at the hosiery narrowings in order to effect the transfer of such loops, and the consequent formation of openings in the fabric, together with means for continuing the knitting of the fabric of the full width for a substantial plurality of courses beyond said openings, and continuing in such courses the introduction of the separate warp threads into their same needle wales as before.

3. In a full-fashioned hosiery knitting machine having knitting needles and cooperating sinkers, etc. to form successive courses of regular loops of the main knitting thread; main thread carrier means to traverse said main thread from edge to edge of the hosiery blank, warp thread guiding fingers to introduce separate warp threads into different needle wales of the fabric coincidentally with the laying of the respective courses of the loops of the main knitting thread; means laterally to transfer or shift loops each composed both of the main knitting thread and a correlated warp thread to provide openings in the fabric, together with means for continuing the knitting of the fabric of the full width for a substantial plurality of courses beyond said openings and continuing in such courses the introduction of the separate warp threads into their same needle wales as before.

4. In a full-fashioned hosiery knitting machine having knitting needles and cooperating sinkers, etc. to form successive courses of regular loops of

a main knitting thread; main thread carrier means to traverse said main thread from edge to edge of the hosiery blank; warp thread guiding fingers to introduce a series of warp threads into different needle wales of the fabric coincidentally with the laying of the respective courses of said loops, transfer points adapted to enter loops each composed of the main knitting thread and the correlated warp thread, means to shift said points to effect the transfer of loops and the consequent formation of openings together with means for continuing the knitting of the fabric of the full width for a substantial plurality of courses beyond said openings, and continuing in such courses the introduction of the separate warp threads into their same needle wales as before.

5. In a full-fashioned hosiery knitting machine having spring beard needles and cooperating sinkers, etc. to form successive courses of regular loops of a main knitting thread; main thread carrier means to traverse said main thread from edge to edge of the hosiery blank; warp thread guiding fingers to introduce separate warp threads, one into each needle wale of the fabric, coincidentally with the laying of the respective courses of the loops of the main knitting thread; and means laterally to transfer or shift loops of the main and warp threads inward at substantially the leg narrowing positions.

6. In a full-fashioned hosiery knitting machine having spring beard needles and cooperating sinkers, etc. to form successive courses of regular loops of a main knitting thread; main thread carrier means to traverse said main thread from edge to edge of the hosiery blank; warp thread guiding fingers, one for each needle wale, to introduce a separate warp thread into each loop of each needle wale of the fabric coincidentally with the laying of the respective courses of said loops; narrowing points adjacent each selavage portion of the fabric and means to move the same toward each other to transfer or shift loops of the main thread and correlated warp threads, thereby to provide two opposite inclined lines along which the fabric outside thereof may be subsequently trimmed.

7. In a full-fashioned hosiery knitting machine having knitting needles and cooperating sinkers, etc. to form successive courses of regular loops of the main knitting thread; main thread carrier means to traverse said main thread from edge to edge of the hosiery blank; warp thread guiding fingers to introduce separate warp threads into different needle wales of the fabric coincidentally with the laying of the respective courses of the loops of the main knitting thread; and means laterally to transfer or shift loops composed of the main and warp threads inward at substantially the leg narrowing positions.

8. In a full-fashioned hosiery knitting machine having knitting needles and cooperating sinkers, etc. to form successive courses of regular loops of a main knitting thread; main thread carrier means to traverse said main thread from edge to edge of the hosiery blank; warp thread guiding fingers to introduce a series of warp threads into different needle wales of the fabric coincidentally with the laying of the respective courses of said loops; narrowing points adjacent each selavage portion of the fabric; and means to move the same toward each other to transfer or shift loops composed of the main thread and correlated warp threads, thereby to provide two opposite inclined lines along which the fabric outside thereof may be subsequently trimmed.

9. In a full-fashioned hosiery knitting machine having upright spring beard needles and cooperating sinkers, etc. to form successive courses of regular loops of a main knitting thread; main thread carrier means mounted at one side of the needle series and adapted to be traversed from edge to edge of the hosiery blank, warp thread guiding fingers to introduce separate warp threads, one into each needle wale of the fabric, coincidently with the laying of the respective courses of the loops of the main knitting thread; said warp thread guiding fingers being mounted at the opposite side of the needle series from said thread carrier, and so as to depend into position adjacent to the needles so as to be moved between said needles to lay their threads; narrowing points for insertion into loops to effect lateral transfer thereof, and means to operate said points so as to provide inclined lines of indicating openings at the leg narrowing zone as a guide for trimming off fabric laterally beyond said openings.

10. In a full-fashioned hosiery knitting machine having upright spring beard needles and cooperating sinkers, etc. to form successive courses of regular loops of a main knitting thread; main thread carrier means mounted at one side of the needle series and adapted to be traversed from edge to edge of the hosiery blank; warp thread guiding fingers to introduce separate warp threads, one into each needle wale of the fabric, coincidently with the laying of the respective courses of the loops of the main knitting thread; said warp thread guiding fingers being mounted at the opposite side of the knitting series from said thread carrier and so as to depend into position adjacent to the needles so as to be moved between said needles to lay their threads; and means laterally to transfer or shift loops composed of the main knitting thread and correlated warp threads inward at substantially the leg narrowing positions.

11. In a combination according to claim 7, means to retard or delay the inward movement of the sinkers and dividers at the time of said transfer, for the purpose stated.

12. In a combination according to claim 7, means to prevent substantial contact of the sinkers and dividers with the last formed course of loops, during the said lateral transfer of loops.

13. In a combination according to claim 7, means to apply uniform tension to all the warp threads of a section of said machine during the said knitting and said lateral transfer of loops.

14. In a combination according to claim 7, a single warp beam for all the warps of one section of the machine, and means between said warp beam and the said warp thread guiding fingers to guide each warp thread in a separate path.

15. In a combination according to claim 7, warp beam means for a section of the machine, and a guide plate between said warp beam means and the said warp thread guiding fingers, provided with a separate opening for each warp thread.

16. In a combination according to claim 7, warp beam means for a section of the machine, a guide plate between said warp beam means and the said warp thread guiding fingers, said guide being provided with a separate opening for each warp thread, and means variably to tension the entire set of warp threads substantially at said guide plate.

17. In a combination according to claim 7,

means to hold all the warp thread guiding fingers of a section in fixed relation with respect to each other, and means for permitting manual movement of all of said fingers into non-functioning position.

18. In a combination according to claim 7, means to maintain tension upon all the entire set of warp threads of a section of the machine, and means for manually varying or altering the tension upon said entire set of warp threads as a unit.

19. In a combination according to claim 7, two sets of transfer points constituting the means for lateral transfer of said loops of a section of the machine, means to impart lifting or rising movement to said transfer points with the said loops thereon and to deliver said loops to adjacent needles, and means to retard or delay the inward movement of the sinkers and dividers while said transfer points are delivering said loops.

20. In a combination according to claim 7, two sets of transfer points constituting the means for lateral transfer of said loops of a section of the machine, means to impart lifting or rising movement to said transfer points with the said loops thereon and to deliver said loops to adjacent needles, and means to retard or delay the inward movement of the sinkers and dividers while said transfer points are delivering said loops.

21. That method of knitting a run-proof or strongly run-resistant full-fashioned stocking upon a full-fashioned hosiery knitting machine having spring beard needles, sinkers and dividers, sets of transfer points, weft carrier means and warp thread guiding fingers, which comprises the following steps: knitting the blank for at least the leg of the stocking by forming the loops course by course from a body thread and a separate warp thread for the different needles wales and in so doing moving the warp thread guiding fingers about the needles respectively; and at leg narrowings causing the transfer points each to enter a loop composed of a portion of the main weft thread and a portion of a warp thread, to lift said loops from the respective needles and to deposit them upon adjacent needles.

22. In a method according to claim 21, retarding or delaying the movement of the sinkers and dividers toward the forming fabric while said transfer points are functioning in the said transfer of loops.

23. In a method according to claim 21, retarding or delaying the inward movement of the sinkers and dividers while the said transfer points are depositing their said loops.

24. In a full-fashioned hosiery knitting machine having knitting needles and cooperating sinkers, etc. to form successive courses of regular loops of the main knitting thread; main thread carrier means to traverse said main thread from edge to edge of the hosiery blank, warp thread guiding fingers to introduce separate warp threads into different needle wales of the fabric coincidently with the laying of the respective courses of the loops of the main knitting thread; means acting at the hosiery narrowing so as laterally to transfer or shift loops, each of which is composed of a portion of the main knitting thread and a portion of a correlated warp thread, together with means for continuing the knitting of the fabric of the full width for a substantial plurality of courses beyond said narrowings and continuing in such courses the introduc-

tion of the separate warp threads into their same needle wales as before.

25. In a full-fashioned hosiery knitting machine having knitting needles and cooperating sinkers, etc. to form successive courses of regular loops of a main knitting thread; main thread carrier means to traverse said main thread from edge to edge of the hosiery blank; warp thread guiding fingers to introduce a series of warp threads into different needle wales of the fabric coincidently with the laying of the respective courses of said loops, transfer points adapted to enter loops each composed of the main knitting thread and the correlated warp thread, means to shift said points at the hosiery narrowings in order to effect the transfer of such loops, together with means for continuing the knitting of the fabric of the full width for a substantial plurality of courses beyond said narrowings, and continuing in such courses the introduction of the separate warp threads into their same needle wales as before.

26. In a full-fashioned hosiery knitting machine having knitting needles and cooperating sinkers, etc. to form successive courses of regular loops of the main knitting thread; main thread carrier means to traverse said main thread from edge to edge of the hosiery blank, warp thread guiding fingers to introduce separate warp threads into different needle wales of the fabric coincidently with the laying of the respective courses of the loops of the main knitting thread; means laterally to transfer or shift loops each composed both of the main knitting thread and a correlated warp thread, together with means for continuing the knitting of the fabric of the full width for a substantial plurality of courses beyond said transferred loops and continuing in such courses the introduction of the separate warp threads into their same needle wales as before.

27. In a full-fashioned hosiery knitting machine having knitting needles and cooperating sinkers, etc. to form successive courses of regular loops of the main knitting thread; main thread carrier means to traverse said main thread from edge to edge of the hosiery blank; warp thread guiding fingers to introduce separate warp threads into different needle wales of the fabric coincidently with the laying of the respective courses of the loops of the main knitting thread;

and means laterally to transfer or shift loops composed of the main and warp threads inward at narrowing positions to provide fashioning marks and shaping of the hosiery, and the positioning of the selavage wales in the direction of the fashioning, so that the subsequent seaming may be made along the wales instead of across them.

28. A full-fashioned hosiery knitting machine according to claim 7, wherein said warp thread guiding fingers are respectively set slightly nearer the needle at one side of each guide than at the other side of that guide, for the purpose stated.

29. A full-fashioned hosiery knitting machine according to claim 7, wherein, said warp thread guiding fingers are set slightly nearer the needles next to the left viewing the front of the machine, for the purpose stated.

30. In a full-fashioned hosiery knitting machine having knitting needles and cooperating sinkers, etc. to form successive courses of regular loops of the main knitting thread; main thread carrier means to traverse said main thread from edge to edge of the hosiery blank; warp thread guiding fingers, one for substantially each knitting needle, so as to introduce the separate warp threads into the different needle wales of the fabric coincidently with the laying of the respective courses of the loops of the main knitting thread means laterally to transfer or shift inwardly at narrowing positions loops composed of the main and warp threads, and means whereby during said lateral transfer or shifting of loops the warp thread fingers are moved to a greater distance from the needles than they occupy during their warp thread positioning movements.

31. A full-fashioned hosiery knitting machine according to claim 7, having a weft thread guide at one or both edges of the series of knitting needles to insure the proper positioning of the new incoming weft thread.

32. In a combination according to claim 7, and as a part of the mechanism for operating the knitting needles, a needle cam against which a follower is adapted to work, and a box cam to cooperate in holding said follower against the periphery of the needle cam.
